CLAIM

The ornamental design for a combined radio, cassette player and cassette recorder, as shown and described.

DESCRIPTION

FIG. 1 is a front elevation view of a combined radio, cassette player and cassette recorder showing my new design; FIG. 2 is a top plan view thereof;

FIG. 3 is a right side elevation view thereof, the opposite side being a mirror image of the side illustrated;

FIG. 4 is a rear elevation view thereof; and,

FIG. 5 is a bottom view thereof.

FIGS. 3 and 4 show the handle in an alternate position.
